Primary Examiner — Janice Hallmark*Assistant Examiner* — Adedoyin Taiwo Odeyale(57) **CLAIM**

The ornamental design for a high pressure water gun, as shown and described.

DESCRIPTION

FIG. 1 is a perspective view of a high pressure water gun showing my new design;

FIG. 2 is a front elevational view thereof;

FIG. 3 is a rear elevational view thereof;

FIG. 4 is an enlarged left side elevational view thereof;

FIG. 5 is an enlarged right side elevational view thereof;

FIG. 6 is a top plan view thereof; and,

FIG. 7 is a bottom plan view thereof.

The broken lines throughout the drawing figures depict portions of the high pressure water gun that form no part of the claimed design.

1 Claim, 7 Drawing Sheets(56)
